CLAIM

The ornamental design for a tire tread, as shown and described.

DESCRIPTION

FIG. 1 is a perspective view of tire tread in accordance with the present disclosure;

FIG. 2 is a front view thereof;

FIG. 3 is a side view of a first side thereof;

FIG. 4 is a side view of a second side thereof; and,

FIG. 5 is an enlarged fragmentary view thereof.

It is understood that the pattern repeats uniformly throughout the circumference of the tread. The broken lines defining the sidewall, inner bead, and the peripheral boundary between the tire tread and the sidewall depict unclaimed subject matter and form no part of the claimed design.
